ILLINOIS.

COMBINATION DRAFT-ARM.

1,396,915.

Specification of Letters Patent. Patented Nov. 15, 1921.

Application filed December 2, 1920. Serial No. 427,697.

To all whom it may concern:

Be it known that we, CHARLES L. BASTIAN and HJALMAR MATHISEN, citizens of the United States, residing at Chicago, in the county of Cook and State of Illinois, have invented certain new and useful Improvements in Combination Draft-Arms, of which the following is a specification.

This invention relates to dispensing devices for carbonated beverages but more particularly to combination draft arms or faucets for controlling the discharge of syrup and carbonated water.

The primary object of the invention is to provide a draft arm which is simple, and durable in construction and may be quickly and easily operated.

Further objects of the invention are to provide an improved valve construction for controlling the flow of syrup to and from a measuring chamber, to provide means for shutting off the supply of syrup independently of the water, and to prevent leakage of the syrup.

The many other objects and advantages of the invention will be better understood by reference to the following specification when read in connection with the accompanying drawings illustrating a selected embodiment thereof in which:

Figure 1 is a central vertical section of my invention; and

Fig. 2 is a section on the line 2, 2 of Fig. 1.

In the drawing my improved draft arm comprises a casing 5 mounted at 6 on the usual standard through which the carbonated water is admitted to the draft arm. This casing 5 is provided with a discharge nozzle 7 of the usual type. A cylindrical casing 8 is mounted on the upper portion of the casing 5 to support the syrup supply reservoir 9, and form a conduit for the syrup therefrom. A measuring chamber 10 within the casing 8 and spaced therefrom has its lower threaded end 11 seated in the upper wall of the casing and the interior wall of this chamber 10 is preferably threaded to receive the correspondingly threaded head of an adjusting plunger 12 provided with operating stem 13.

A valve chamber 14 is provided within the casing 5 to contain and form a seat for the rotary valve 15 which controls the flow of the syrup from the reservoir 9 to the meas-

uring chamber 10 and from this chamber to the discharge nozzle 7. The valve 15 is cylindrical in form and is provided with a stem 16 controlled by an operating handle 17'. A channel 18 is formed in the periphery of the valve 15 and extends longitudinally thereof to provide means of communication between a passage 19 leading from the reservoir 9 to the valve chamber and a passage 20 from this chamber to the measuring chamber 10. The valve 15 is provided with an axial aperture 21 to receive and form a seat for a rotary valve 22. A passage 23 extends through the valve 22 and is adapted to register with oppositely disposed passages 24 in the valve 15. The passages 24 communicate with one end of the channel 18. The valve 22 has a stem 25 extending through the stem 16 of the valve 15 and an operating handle 26 is secured upon the outer extremity of this stem.

A discharge passage 27 in the casing 5 connects the chamber 14 with the nozzle 7. A perforated washer or packing ring fits in the mouth of this passage and is pressed firmly against the face of the valve 15 by the gland 29 to prevent leakage of the syrup.

The carbonated water enters the casing 5 through the inlet passage 30 which is preferably provided with a pressure regulator 31 to permit adjustment of the draft arm for varying water pressures. The valve 32 and the parts operating in conjunction therewith to control the flow of the water to the nozzle 7 form no part of the present invention and further description is considered unnecessary. An arched operating yoke 17 joins the stems of the valves 15 and 32 so that these valves are operated simultaneously by the handle 17'.

In the operation of the draft arm the yoke 17 normally rests in its raised position as indicated in the drawing. The channel 18 in this position communicates with the passages 19 and 20 and permits flow of syrup from the reservoir to the measuring chamber. The capacity of this chamber depends upon the position of the adjusting plunger therein. This plunger should be set to provide uniformly the charge of syrup desired. To discharge the syrup contained in the measuring chamber the valve 15 is rotated by the handle 17' until the passages 20, 23, 24 and 27 are in registration. The rotation

of the valve 15 closes the communication of the passage 19 with the channel 18 so that no syrup can flow from the reservoir to the measuring chamber or directly to the nozzle 7. The handle 17' is returned to the raised position as soon as the charge of syrup in the measuring chamber has been emptied and sufficient water drawn. The measuring chamber automatically refills with syrup as soon as the handle 17' is raised. When water without syrup is desired, the handle 26 is operated to rotate the valve 22 sufficiently within the valve 15 to move the passage 23 out of registration with the passage 24. The yoke 17 may now be raised to operate the valve 32 but no syrup is released from the measuring chamber.

This draft arm is exceedingly simple and durable in construction and may be quickly and easily operated. The rotary valve simplifies both the construction and the operation. Valves in draft arms are subjected constantly to sticky syrups which tend to cake upon them and prevent proper seating so that leakage of syrup quite generally occurs. The present valve is always in firm contact with its seat so that the contacting surfaces form a protection for each other and there is practically no opportunity for the collection of deposits. The supplementary control for the syrup supply enables syrup and water to be drawn simultaneously or water to be drawn without syrup. The entire device has few parts and these may easily be disassembled and cleaned.

We are aware that many changes in construction and in arrangement of parts may be made without departing from the invention and we reserve the right to make all such changes as fairly fall within the scope of the following claims.

We claim:

1. A dispensing device for liquids comprising a casing, a valve chamber in said casing, a fluid supply reservoir communicating with said chamber, a measuring receptacle communicating with said chamber, a discharge passage leading from said chamber, and a rotary cylindrical valve member in said chamber provided with a passage therein to establish communication between said reservoir and said receptacle in one position of said member and between said receptacle and said discharge passage in another position of said member. 50

2. A dispensing device for liquids comprising a casing, a valve chamber in said casing, a measuring receptacle connected by a passage with said chamber, a discharge passage from said chamber, a rotary valve 60 having a passage therethrough to register with said passages to establish communication between said receptacle and said discharge passage, and means operable independently of said rotary valve to cut off said 65 communication when said passages are in registration.

3. A dispensing device for liquids comprising a casing, a valve chamber in said casing, a measuring chamber connected by a 70 passage with said valve chamber, a discharge passage from said valve chamber, a rotary valve having a passage therethrough to register with said passages to establish communication between said measuring 75 chamber and said discharge passage, and a second rotary valve within the first mentioned valve and operable independently thereof to cut off said communication when said passages are in registration.

CHARLES L. BASTIAN.
HJALMAR MATHISEN.
